UNITED STATES PATENT OFFICE.

LEO O. SMITH, OF NEWARK, NEW JERSEY.

IMPROVEMENT IN COACH-PAD TREES.

Specification forming part of Letters Patent No. **177,081**, dated May 9, 1876; application filed September 9, 1874.

To all whom it may concern:

Be it known that I, LEO O. SMITH, of Newark, New Jersey, have invented an Improvement in Harness-Pad Plates or Trees, of which the following is a specification:

The object of this invention is to enable a manufacturer to make a simple, durable, and cheap harness-pad, requiring but little skill and labor in the covering and mounting of its plate or tree, and but little stuffing, and which, by reason of its plate or tree being cast in one piece, may the more readily, if desired, be made in great numbers, of uniform size and shape.

Heretofore harness-pads have been made with their plates in separate pieces, the bottom piece being struck up and fitted to the top piece, and the two united together mainly by the leather covering. Such harness-pads are more complicated in structure, more difficult to cover and finish, and are more likely to get out of repair than a harness-pad built upon the plate or tree hereinafter described.

This invention, therefore, consists in a pad plate or tree cast substantially in the form illustrated in the drawing, and having but one piece or web to form both its top and bottom, which web is provided with suitable flanges.

In the drawing, A is the main body or web of the plate or tree. a is a perforated flange, to which the leather covering may be secured. b is a hole in the main body or web A, through which either a check-hook or a terret may be inserted, and secured by means of a nut in the recess c. d is a perforated web cast over a recess in the main web A, which recess is open at one end, and partially closed on top by the perforated web d. Into this recess is passed an ordinary burr or terret-nut, having its shoulder projecting up through the hole d² in the web d, and secured in place by a thin strip of metal, e.

This strip may be riveted at either end to the web A, if desired. The burr can thus be removed, when repairing the pad, by either sliding or springing down the strip e without cutting off any rivets.

Burrs, as ordinarily secured, are riveted through their flanges to the tree or plate, which rivets must be cut, in order to remove said burrs.

Between the ribs g g, cast upon the top of the main web A, are placed ordinary burrs or nuts, for receiving necessary screws, terrets, or hooks. These burrs or nuts so held likewise require no rivets to secure them in place.

It is evident, however, that the necessary burrs or nuts may be secured to the web A in any manner desired without departing from the principle of my invention of casting a pad plate or tree with such a distribution of metal in one piece as to produce a shape necessarily requiring a minimum of material for the stuffing, covering, and mounting of said tree.

I am aware that jockey or harness saddle-trees have heretofore been cast in one piece; but such trees cannot be used interchangeably at pleasure for either a harness-saddle or a harness-pad. By a jockey-saddle or a harness-saddle I mean the article known by such name to harness-makers, which is used only for single harness. By a coach-pad or harness-pad I mean the article known by such name to harness-makers, and which is used only for double harness.

Having thus fully described this harness-pad plate as of my invention, I claim—

As an article of manufacture, a harness-pad plate or tree cast in one piece, in the shape substantially as described, consisting of a main body or web, A, provided with perforated flanges a, recessed web d, and ribs g g, in the manner substantially as described, for the purposes set forth.

In testimony that I claim the foregoing as my own invention I affix hereto my signature in presence of two witnesses.

LEO O. SMITH.
